(57) CLAIM

We claim the ornamental design for a multi-panel computer display, as shown and described.

DESCRIPTION

FIG. 1 is a front perspective view of our design for a multi-panel computer display.

FIG. 2 is a rear perspective thereof.

FIG. 3 is a front elevation thereof.

FIG. 4 is a rear elevation thereof.

FIG. 5 is a right side view thereof. The left and right sides of our design are mirror images of each other.

FIG. 6 is a top view thereof; and,

FIG. 7 is a bottom view thereof.

Portions of the drawings shown in broken lines are for illustrative purposes only and form no part of the claimed design.

1 Claim, 7 Drawing Sheets
